UNITED STATES PATENT OFFICE

2,452,848

ELECTRIC PIANO ACTION

James F. Goodwin, Los Angeles, Calif.

Application May 29, 1944, Serial No. 537,871

7 Claims. (Cl. 84—246)

1

This invention appertains to improvements in piano actions generally, and more particularly to electrically powered and controlled types thereof.

The invention has among its several objects to provide an action of this class and one that is of extreme simplicity in design and operation, appreciably less expensive to manufacture, and much faster in execution of key movements as compared to the heretofore known or conventional types of such actions.

With these and other objects and advantages of equal importance in view, the invention resides in the certain new and useful combination, construction and arrangements of instrumentalities, parts and circuits, as will be hereinafter more fully described, set forth in the appended claims, and illustrated in the accompanying drawings, in which:

Figure 1 is a fragmentary plan view of a section of the improved piano action, in accordance with the invention;

Figure 2 is a vertical transverse section taken on the line 2—2 of Figure 1, and showing a single key unit of the action at a position of rest;

Figure 3 is a view similar to that of Figure 2, but showing the changed position of the unit parts upon the depression of the key;

Figure 4 is a diagrammatical view of the electric power and control circuits;

Figure 5 is a top plan view of a circuit and damper control unit associated with each of the keys;

Figure 6 is a perspective view of an angled element or stop for limiting the operative of the circuit closer or controller;

Figure 7 is a view similar to that of Figure 6, but showing the damper element; and

Figure 8 is another perspective view of an element or pin for transmitting the key movement to the damper for its displacement from string contact.

Referring to the drawings, wherein like characters of reference denote corresponding parts throughout the several views, the embodiment of the invention, as is exemplified therein, is comprised in a foundation, in the form of an angled frame, preferably of wood, that extends the full length of the case (not shown) and is made up of a beam 11 and a rail 12 rising from its front edge. A standard keyboard (not shown) is disposed in spaced relation to the front side of the foundation and the keys 13 are individually supported from the rail 12 by flat steel springs 14. Extending parallel to the rail 12, in the space

2

between it and the inner ends of the keys 13, is a cam-like element 18 that may take the form of a metal rod, oval in cross-section, mounted for turning movements to adjust the tension of the springs 14. The rod 18 has bearing throughout its length on the top edge of a bar or strip 19 that is secured to the front side of the rail 12. The springs 14 have their inner ends secured, as at 15, to the top side of the rail 12 and their forwardly directed ends, as at 16 and 17, to the top sides of the keys 13; the securement 11, at the outer ends of the springs 14, having the form of a headed pin that extends downwardly through the keys 13, so that their lower ends project well below the latter, as at 17'.

Secured in spaced relation with respect to each other along the foundation 11 and extending transversely thereof are elongated members 20, one for each of the keys 13, the forward ends of 20 the same underlying the latter and their other ends projecting rearwardly and terminating in proximity to respective of the strings S. These members 20 are preferably in the form of metal strips and each constitutes a support for a complete operating unit of the action.

Pivotedly mounted, as at 22 and 25, on the lower side of each of the supporting members 20 is a pair of arms 21 and 24 which are, in turn, pivoted as at 23 and 26, respectively, to a rod 27 30 that has a damper-head 28 affixed to its rearwardly directed end and normally engaged with its associated string S. The arms 21 and 24 suspend the rod 27 in parallel relation to the lower side of a supporting member 20, the arm 24 having pivoted connection therewith inwardly from the damper-head 28 and the arm 21 immediately at its forward end. The arm 21, at its upper pivoted end, is integral with another arm 21' that extends in substantially right angular relation to the same and has its free end underlying an aperture formed in the supporting member 20 in line with an actuating pin 29 35 pivotally secured to the under side of a key 13 by means of apertured ears 29', so that when the latter is depressed the pin 29 will likewise depress the arm 21' and cause the arm 21 to move the rod 27 in a direction to withdraw the damper-head 28 from its contact with a string S to free the string for vibration when it is struck.

Rising from each supporting member 20, in rear of the foundation 11, is a pair of brackets 30 which support a horizontally disposed solenoid 31 on their upper ends. The movable core 32 of the solenoid 31 has its rearwardly directed end provided with a felt percussion-head 33 and

its other or forward end connected through a coiled spring 34 to a rebound damper 35 that is secured to the rear side of the foundation 11. The rebound damper 35 is in the form of a metal plate and has a felt pad 36 interposed between it and the opposed side of the foundation 11 to cushion the core 32 in its rebound motions.

For controlling the operation of a solenoid 31, a movable contact 37 is mounted on the lower side of a supporting member 20 and is comprised in a length of spring metal that is secured at one end to the supporting member and has its other end extending forwardly beyond the foundation 11 and underlying an aperture 38 formed in the supporting member 20 in line with the depending end 17' of the securing pin 17 carried by a key 13. Cooperative with the movable contact 37 is a stationary contact 39 that is mounted in the supporting member 20 and insulated therefrom in-sulation 39'.

As is best shown in Figure 4, the electrical connections for the several action units, are as follows:

A transformer 40 is conveniently mounted within the case (not shown) and is connected to an outside line from a suitable source of current supply. Leads 41 and 42 extend from the terminals of the transformer 40 for the parallel connection across the same of the several action units. For each action unit, a branch lead 43 is extended from, for instance, the main lead 41 to the securing 15 of a spring key support 14 to the foundation rail 12, thus placing the spring support and the securing pin 17, carried by the key 13, in the circuit. A conductor 44 extends from the stationary contact 39 on a supporting member 20, and connects one terminal of the coil of a solenoid 31, while the other terminal of the latter is, in turn, connected by a conductor 45 to the other of the main leads 42.

In the operation of an action unit as thus provided, whenever a key 13 is depressed, the extension 17' of the contact pin 17, passes downwardly through the aperture 38 in the supporting member 20 and bears against the free end of the movable contact 37, closing the circuit therethrough on the stationary contact 39. Current will immediately flow from the transformer 40, by way of the main lead 41, the branch conductor 43, the spring support 14, the contact pin 17 and 17' to the movable contact 37 and through it to the stationary contact 39, from whence it will pass by way of the conductor 44 to one terminal of the coil of a solenoid 31 and from the other terminal of the latter, by way of the conductor 45, to the main lead 42 and back to the transformer 40. With the depression of the key 13, the pin 29, also depending therefrom, strikes the upper portion 21' and depresses it, causing the pivoted arm 21 to move the rod 27 in a direction to withdraw the damper-head 28 from its contact with a string S, which is then free to vibrate when struck by the percussion-head 33 on the solenoid core 32. After striking the string S, the percussion-head 33 and the core 32 are quickly returned to normal position by the action of the coiled spring 34, upon the breaking of the circuit between the movable contact 37 and the stationary contact 39. The circuit is completed but momentarily by the initial engagement of the contact pin 17 and 17', with the movable contact 37, since continued depressing motion of the key 13 results in the separation of the latter from the stationary contact 39.

In order to prevent the movable contact 37

from maintaining the engagement between it and the pin 17 and 17', during the recession of the key 13 to its normal position of rest, which would otherwise result in a repeat closing of the circuit

6 at the stationary contact 39, an angled member is pivoted, as at 46, to the upper side of the supporting member 20, and has one arm 47 depending through an opening in the latter for movement into and out of engagement with the free 10 end of the movable contact 37, during the depressing and lifting motions of the key 13. The other arm 47', of this angled member, is counter-weighted, as at 48, to normally hold the depending arms 47 against the edge of the free end of 15 the movable contact 37, when the action unit is inoperative. Thus, when a key 13 is fingered and the movable contact 37 is depressed by the contact pin 17, and 17', the depending arm 47 is moved by the gravitational action of the counter-weight 48 into the return path of the movable contact 37 and prevents it from continuing in engagement with the contact pin 17 and 17'. The depending arm 47 is withdrawn from the path of the movable contact 37, with the recession movement of the key 13, just before the key reaches its normal position of rest, by the action of an enlargement 29', formed on the pin 29, which engages the under side of the arm 47' and lifts it to its normal position.

20 The upper arm 47' is provided with an apertured enlargement 47'' in which the pin 29 operates, the enlargement 29' of the latter being located below the enlargement 47'' for its cooperation therewith. Also, the lifting movement of 25 the pin 29 frees the angled member 21 and 21' to allow gravitational movement to the rod 27 for the return of the damper-head 28 into engagement with the string S to check the vibration previously imparted to it by the percussion head 33.

30 From this example of the invention, the advantages afforded by its simplicity in design, construction and assembly will be obvious to those skilled in the art to which it relates, it being 35 particularly noted that there are but seven moving parts involved in the makeup of each action unit which effects a marked saving in expense of manufacture and upkeep, both with respect to labor and materials.

30 Having thus fully described my invention, it is to be understood that various changes in design and arrangement of parts, as well as in minor details of construction, may be resorted to, without departing from the spirit of the invention, or its scope as claimed.

What I claim is:

1. In an electrically powered piano, including a keyboard, an individual action for each key and its associated string, said action comprising 60 a string damper a rod supporting said damper, a percussion element, a current source, electromagnetic means for actuating the percussion element, a circuit closer cooperative with the key for energizing the electromagnetic means during the initial fingered movement of the key, arms pivotally connected to said rod means on each key coacting with one of the arms on said rod for withdrawing the damper from the string simultaneously with the depression of said key and with the operation of the percussion element, a coil spring for returning the percussion element to its normal position of rest, the upward movement of said key after its depression releasing the damper for its return by gravity to its normally engaged position with the string.

2. The piano as in claim 1, with an individual support for each action unit extending in a plane below and rearwardly of a key.

3. The piano as in claim 1, with a foundation mounted in rear of the keyboard and co-extensive therewith, and an individual support for each action unit mounted on the foundation and extending in a plane below and rearwardly of a key.

4. The piano as in claim 1, with means actuated by the key movement for holding the circuit closer on open circuit during the recession movement of the key and to allow a quick rebound of the percussion element to its normal position of rest.

5. The piano as in claim 1, with means operable with the key during its depression movement for holding the circuit closer on open circuit during the recession movement of the key, said means being actuated from the key in its latter movement to effect the release of the circuit closer and the damper for their simultaneous return to normal positions.

6. The piano as in claim 1, with the electromagnetic means having the form of a solenoid

10

and the percussion-head mounted on the end of its movable core within striking distance of the string.

7. The piano as in claim 1, with the electromagnetic means having the form of a solenoid and the percussion-head mounted on the end of its movable core and a spring means cooperative with the core for effecting the rebound of the percussion head from striking position.
